ABSTRACT: This invention relates to a liquid cooled radiation source wherein a silicon coolant is made to flow through a chamber at least partially enclosing the radiation source to remove the heat produced by the radiation source. A dye is added to the liquid coolant to act as a filter to remove undesired wavelengths of radiation from the beam leaving the radiation source.

LIQUID COOLED RADIATION SOURCE WITH FILTER

BACKGROUND OF THE INVENTION

In some high energy radiation systems, such as used in night aerial photographic reconnaissance, or night viewing systems, cooling, to dissipate heat generated by the high energy radiation source, is sometimes desirable. With such systems it is necessary to reduce or eliminate all radiation other than that of the wavelengths which match the sensitivity of the detector being used. Air has been used to cool the filter medium in prior art systems, however this has not been entirely satisfactory since it has not eliminated cracking of the filter in all cases.

SUMMARY OF THE INVENTION

According to this invention the filter cracking problem has been overcome by having the light source surrounded by a liquidtight chamber through which a silicone oil coolant flows to carry away the heat produced by the radiation source and by adding an oil soluble dye to the coolant to act as a filter to remove the undesired radiation from the beam leaving the radiation source. The coolant is pumped through the chamber and then to a heat exchanger so that the coolant may be recirculated through the chamber. Before being returned to the chamber the liquid is filtered to remove any solid particles that might form in the liquid.

BRIEF DESCRIPTION OF THE DRAWING

The single FIGURE of the drawing is a schematic diagram partially in block form showing the radiation and protection and filtering system of the invention.

DETAILED DESCRIPTION OF THE INVENTION

In the drawing reference numeral 10 shows a radiation source, which may, for example, by a Xe, Kr, or Ar lamp which emits radiation when excited by a high frequency from signal source 12 which is supplied to the coil 14. A usual type of reflector 16 is provided on the inner surface of chamber 18. A window 19 transparent to the desired radiation closes one end of the chamber 18.

A coolant 21 such as silicone having the formula

to which a dye such as oil red dye having the formula

has been added, is supplied to the chamber 18 from supply 20 by means of a pump 22. The coolant after leaving pump 22 is passed through a liquid filter 24, before it is supplied to chamber 18, to remove any solid particles that might be in the liquid. The coolant leaving the chamber 18 is passed through a heat exchanger 26 before it is returned to the liquid supply 20.

In the operation of the device the silicone liquid is pumped from supply 20 through filter 24 and into chamber 18 to cool 10 the radiation source 10. The coolant leaving chamber 18 is passed through the heat exchanger 26 before it is returned to coolant supply 20. The dye in the coolant 21 absorbs substantially all of the undesired wavelengths so that only radiation of the desired wavelengths leave the window 19.

15 While a particular oil dye has been described any oil soluble dye which will remove undesired wavelengths may be used. Also while all silicone oils are not miscible with all oil dyes any silicone oil may be used which is miscible with the particular dye used.

20 There is thus provided a radiation system in which the heat from the radiation source is readily dissipated and wherein undesired wavelengths are substantially eliminated from the radiation beam.

I claim:

25 1. A device for providing radiation of a predetermined wavelength comprising: a radiation source which is excited by a high frequency signal supplied to coil surrounding the radiation source; a liquidtight chamber; said radiation source being at least partially enclosed within said chamber; a transparent

30 window in said chamber; reflecting means, on the wall of said chamber for directing radiation from said source through the transparent window; a silicon oil, within said chamber; said silicon oil being of the class having the formula

35 an oil soluble dye, miscible with said silicon oil, within said chamber, whereby undesired wavelengths are absorbed; means, including an external flow path with a liquid coolant

40 supply, a pump and a liquid filter between the pump and the chamber, for providing a flow of silicone oil and dye through said chamber; means in the external flow path for removing heat from said silicone oil whereby the dyed silicone oil acts as filter and a coolant for the radiation source.

45 2. The device as recited in claim 1 wherein said dye is an oil red dye having the formula
